United States Patent Office

Des. 210,673
Patented Apr. 2, 1968

210,673

PLAYING BOARD FOR GOLF GAME

Earl D. Sullivan, 5210 Vale Drive,
Carmichael, Calif. 95608

Filed Sept. 6, 1966, Ser. No. 3,737

Term of patent 14 years

(Cl. D34—5)

FIG. 1

FIG. 2

FIGURE 1 is a top plan view of my new design for a playing board for a golf game; and

FIGURE 2 is an end elevational view thereof.

Conventional legible matter is shown in broken lines.

I claim:

The ornamental design for a playing board for golf game, substantially as shown and described.

References Cited

UNITED STATES PATENTS

D. 39,517 9/1908 Campbell ----- D34—5
1,553,611 9/1925 Harrison ----- 273—134

FOREIGN PATENTS

915,406 1946 France.

MELVIN B. FEIFER, Primary Examiner.